UNITED STATES PATENT OFFICE.

NEVILLE S. DICKINSON, OF GLEN RIDGE, NEW JERSEY, ASSIGNOR TO ELEVATOR SUPPLIES COMPANY, INC., A CORPORATION OF NEW JERSEY.

ELEVATOR SAFETY DEVICE.

Application filed June 18, 1920. Serial No. 330,047.

To all whom it may concern:

Be it known that I, NEVILLE S. DICKINSON, a citizen of the United States, residing at Glen Ridge, New Jersey, have invented 5 certain new and useful Improvements in Elevator Safety Devices, of which the following is a clear, full, and exact description.

My invention relates to elevator safety appliances, and particularly appliances suitable for electrically controlled elevators, and 10 an object of the invention is to provide a suitable arrangement of control whereby it will be impossible to start the elevator unless a certain order of manipulation of the 15 control devices is followed. It is customary to close and latch the elevator gates or hatchway doors, and then to manipulate the starting device. It may often happen that a 20 careless operative will manipulate the starting device before closing the gate at the hatchway at the floor at which the elevator may be. This is a dangerous procedure, and in some States laws have been passed requiring 25 elevators to be equipped with devices whereby it is impossible to start the elevator until all hatchway gates are closed.

A further object of my invention is to prevent the elevator moving under control of the starting device if this device is manipulated prior to the closing of the elevator 30 gates, even though said gate or gates are subsequently closed, and until said starting device is again moved to neutral position.

A still further object of my invention is 35 to provide a safety appliance which is readily adaptable to elevator installations now in use, and particularly to elevators which are started under control of a hand rope.

Other objects and important features of 40 the invention will become apparent from the following detailed description and claims when considered in connection with the accompanying drawings, in which I have shown my invention in diagrammatic form 45 and as applied to rope-controlled elevator.

Referring to the drawings, 1 indicates a hand rope passing over a pulley 2 at the bottom of the elevator shaft and over a pulley 3 which may be situated near the top thereof. 50 As is usual in this type of elevator, the shaft 4 carrying the pulley 3 may also carry an electric controller for properly controlling the current supplied to the motor to start the same with the proper acceleration and

to reverse the same. The particular construction of this controller forms no part of my present invention and may be of any suitable construction. I have therefore not shown the controller in detail, but in practice it is mounted on the shaft 4 and controls 55 an electric circuit 5 leading to the brush 6 of the motor 7. The other brush 8 is in connection with a wire 9 leading to a contact 10 on a rheostat by which the starting of the motor is controlled. The rheostat may be 60 of any suitable and well known construction, and in the diagram I have indicated an arm 11 pivoted at 12; and to the other end of said arm a wire 13 is connected. This wire 65 leads to the controller and is connected thereto at 14. Wires 15 and 16 lead to the motor field 17. A solenoid 18, for cutting out resistance in the motor circuit and having 70 wires 19 and 20, is also provided, which wires also lead to the controller. A dashpot 21 governs the movement of the solenoid core 22 so that the resistances in the rheostat are gradually cut out as the motor starts. A 75 brake drum 23 is provided, and this may be in connection with the motor shaft by means 80 of the shaft 24. Brake shoes 25 bear upon the brake drum and are held thereagainst by the usual springs (not shown). A solenoid 26 connected to the toggle links 27 acts to release 85 said brake shoes when the solenoid is actuated.

The above described elevator control mechanism is of well known construction, and it is in connection therewith that my improvements are adapted to be used with 90 practically no change in the actual structure of the operating mechanism, and with but slight change in the wiring. In the construction now in use, the circuit to the solenoid 26 is supplied through the controller 95 and ordinarily, as soon as the elevator rope 1 is pulled, either in one direction or the other, the solenoid 26 is energized to release the brake shoes. In my improved construction, however, the means for actuating this 100 solenoid forms an important feature of the invention, and the circuit through it is controlled in a novel manner, as will be pointed out later.

The controller is supplied with current by 105 lead wires 28 and 30 connected to a main feed wire 31 on one side of the line, and in the form of mechanism already in use, the

other supply wire 29 leading to the controller is connected directly to the other side of the circuit, and in operation, any pull upon the elevator rope 1 from normal position 5 will cause the release of the brake shoes through energization of the solenoid 26 and the closing of such contacts within the controller as would cause the current to pass through the motor in a direction to cause the 10 elevator to move up or down, depending upon whether the rope 1 was pulled upwardly or downwardly from normal position.

In my improved construction, however, the 15 lead wire 29 does not go directly to the other side of the line, but instead, said circuit leads from 29 through the wire 32 to a contact 33 forming part of a switch 34, which switch is under the control of a line switch magnet 35; and when said line switch magnet is energized, its core 36 is pulled up, thereby bringing together the contacts 33 and 34. The elevator operating circuit then continues from 33 through 34 to the contact 37, 25 wire 38, wire 39, wire 40 to the other side of the line at 41, being connected at this point with the other main feed wire 42. Whenever the line switch magnet 35 is energized, the elevator operating circuit supplies 30 current to the controller and the elevator motor may be started.

In order to control the energization of said line switch magnet and therefore control the elevator operating circuit, I provide a switch 35 which is closed by movement of the elevator rope in either direction. While various devices may be employed to accomplish this, in the particular embodiment of the invention illustrated, I have shown a ball 43 and 40 a ball 44, said balls being fixed to the elevator rope at suitable points, said balls being close together, and extending between them is an arm 45 fixed to a shaft 46, said shaft carrying a disc having an electric contact 47 extending through a considerable portion of its circumference. Said disc, however, 45 has an insulated portion 48 upon which an electric contact 49 normally rests. A second electric contact 50 rests upon the metallic portion 47. A wire 51 is connected to the contact 50 and is connected through the wire 52 to the main feed wire 42, a fuse 53 being connected between the wires 52 and 42 at the points 54 and 55. The purpose and function 55 of this fuse will be explained later. From the contact 49 a wire 56 is connected through the wire 57 to the line switch magnet 35, the circuit through said magnet including a wire 58, wire 59, contact 60, contact 61, wire 62, wire 63 which may be connected at 64 to the main feed wire 31. Suitable resistance 64' may be interposed in this circuit. Normally the circuit through the line switch magnet 35 is broken at 60-61 and also at 49. 65 Under these conditions, movement of the

elevator rope 1 in either direction will move the arm 45 and cause such rotation of the disc that its metallic contact 47 will engage the contact 49, while the contact 50 remains in electrical engagement with 47. The circuit, however, through the line switch magnet remains broken at 60-61, so that such movement of the elevator rope does not result in starting the elevator, as the operating circuit is still open at 33-37. The arm 45 above referred to is normally maintained in a neutral position by a spring 65 connected to some stationary part 66.

In addition to closing the circuit for the line switch magnet at the elevator starting contact device, actuated by the elevator rope, it is necessary to close the contact 60-61, and this is brought about when the gate contacts are closed. These gate contacts are represented diagrammatically at 67, 68 and 69 and are in series, and when all of them are closed, current will flow from the main line wire 31 to wire 70, through resistances 71 and 72 to the wire 73, through contact 69 wire 74, contact 68 wire 75, contact 67 wire 76, wire 77, wire 78, wire 79, relay magnet 80, wire 81, wire 82, to the point 54 where it passes through the fuse 53 to the other feed wire 42. The relay magnet 80 is provided with a core 83, to which is connected a lever 84 pivoted at 85. The lever 84 is in the form of a bell crank, the other arm 86 of which carries at one end a member 87 to which is connected a switch 88. A spring 89 is connected to the bell crank 84 and normally acts to hold the switch 88 out of engagement with the contacts 60-61. When the gate contacts are all closed and the magnet 80 is energized, switch 88 closes contacts 60-61, and if at that time the elevator rope 105 is actuated to close the elevator operating switch, current will flow through the line switch magnet 35 and this will pull up its core 36 and cause the contacts 33-37 to be bridged by the switch 34, thus permitting 110 current to pass to the elevator operating circuit which is properly distributed by the electric controller already referred to to cause starting of the motor. The elevator will then move up or down according to the 115 direction of pull on the rope 1.

Closing of the gate contacts and subsequent operation of the elevator starting switch is the normal operation. But in case the elevator starting switch is closed prior to the closing of all of the gate contacts, means are provided to prevent closing of the elevator operating circuit even though the gate contacts, or any of them, are subsequently closed.

The means for accomplishing this consist of a shunt circuit including said gate contacts and said elevator starting switch, but not including the relay magnet 80. The member 87 besides carrying the switch 88, 130

also carries a switch 90, bridging contacts 91 and 92 forming part of said shunt circuit, which circuit passes through the gate contacts, through the wires 77-78, 91-92, 5 wire 93, wire 56 to the elevator starting switch and through this to wires 51-52 to 42 if said starting switch is closed. It results, therefore, that if said starting switch is closed prior to the closing of the gate contacts, and said gate contacts are subsequently closed, current will flow through said shunt circuit and the relay magnet 80 will not be energized. Therefore contacts 60-61 will remain open and the line switch magnet 35 10 will not be energized. It will be noted that while the current is passing through said shunt circuit, there is also a circuit formed through said gate contacts and through wires 77, 78, 79, relay magnet 80 and wires 20 81-82 to the other side of the line, but the resistance of the relay magnet 80 is such that this current is small and is not sufficient to cause actuation of the relay magnet, the greater portion of the current flowing 25 through said shunt circuit. Current will continue to pass through said shunt circuit until the elevator starting switch is opened, and when this takes place the solenoid 80 will immediately receive sufficient current to 30 cause it to be actuated, which will result in breaking the shunt circuit at 90-92 and closing the line switch magnet circuit at 60-61. Subsequent closing of the elevator starting switch will then result in the elevator motor being supplied with current.

Not only does the line switch magnet 35 control the closing of the elevator operating circuit, but it also closes a circuit through the brake solenoid 26, and for this 40 purpose the core 36 of the solenoid 35 carries a member 94 which, when the solenoid 35 is energized, bridges the contacts 95 and 96 causing a circuit to be made which leads from the point 41 through wire 40, wire 39, 45 wire 38, contacts 95-96, wire 97, wire 98, wire 99, solenoid 26, wire 100 to the main feed wire 31 at the point 101. Energization of the line switch magnet 35 will, therefore, result in releasing the brake shoes 25.

50 The resistances 71-72 and the fuse 53, included in the circuit through the gate contacts and through the relay 80, furnish a means for protecting the device against accidental grounds. If, for instance, any gate 55 contact should be grounded with the main wire 31, the resistances 71 and 72 would be cut out, and a heavy current will pass through the fuse 53. Under these circumstances, the fuse would be blown and the 60 elevator operating circuit could not be closed. If, on the other hand, a ground occurred between the gate contacts, or any one of them, and the feed wire 42, no current 65 would be supplied to the relay 80 and again the elevator operating circuit controlled by

the line switch magnet 35 would not be supplied with current.

In operation the gate contacts at 67, 68 and 69 are first closed and afterwards the rope 1 is pulled, resulting in the elevator 70 motor being operated. Closing of the gate contacts establishes a circuit from the main feed wire 31, through the wire 70, resistances 71 and 72, wire 73, gate contacts 67, 68 and 69, wire 76, wire 77, wire 78, wire 79 and 75 relay magnet 80, from which magnet the current flows through wires 81 and 82 to the point 54 and across the fuse 53 to the point 55 on the other side of the line. Movement of this magnet breaks contact be- 80tween the terminals 91 and 92 and establishes contact between the terminals 60 and 61 so that current immediately flows from the main feed wire 31 through resistance 64¹, wire 63, wire 62, wire 59, wire 58, through 85² the line magnet 35, whence it flows through wire 57 to contact 49 and contact 50 through wire 51 to the point 54, to the other side of the line. Energization of the line switch magnet 35 bridges the terminals 33, 37 thereby permitting current to flow from the point 41 through the wire 40, wire 39 and wire 38, and terminals 37 and 33, to wire 32, wire 29 and through the controller which has been so positioned by the pull on the rope 1 that 90³ current will flow through the motor 7 to cause the elevator to move in a downward direction, the current passing out of the controller through the wires 28 and 30 back to the other side of the line at 31. 100

This is the normal manner in which the device is intended to function, but if, for any reason, the operative should actuate the rope 1 to put the terminals 49 and 50 into electrical contact before closing all of the gate contacts, then a shunt circuit will be established, as has been described, around the relay magnet 80 and not enough current would flow through said magnet to actuate it and therefore the contacts 60 and 61 will 110 not be electrically connected and the line switch magnet 35 will therefore not be energized, nor the controller supplied with current. It will thus be seen that the usual controller for elevators in systems now installed is placed under control of the line switch magnet 35 of my present improvement and this magnet in turn is under control of the relay magnet 80 which in turn is controlled by the gate contacts. 120

It will also be seen that the brakes normally holding the motor stationary are released under control of the line switch magnet 35 so that unless this magnet is energized, not only is no current supplied to the 125 motor, but no current is supplied to the brake release solenoid 26.

While I have shown and described one practical improvement of my invention, it is obvious that variations may be resorted 130

to without departing from the spirit thereof, and parts of the device may be used without others.

Having thus described my invention, what 5 I claim and desire to secure by Letters Patent is:

1. In an elevator safety appliance, the combination with an elevator operating circuit, of means controlling the closing of 10 said circuit, said means including a relay magnet and gate contacts in series therewith and also including an elevator starting switch, and means preventing the closing of said operating circuit if said elevator switch 15 is closed prior to said gate contacts, said preventing means including a shunt circuit around said relay magnet, said shunt circuit including said elevator starting switch.

2. In an elevator safety appliance, the 20 combination with an elevator operating circuit, and a line switch magnet for closing said circuit, of a relay magnet, gate contacts in series for closing a circuit through said relay magnet, a switch in circuit leading 25 to said line switch magnet, which circuit is closed on actuation of said relay magnet, and an elevator starting switch also in said line switch magnet circuit.

3. In an elevator safety appliance, the 30 combination with an elevator operating circuit, an elevator starting switch and gate contacts, of a line switch magnet for closing said elevator operating circuit, a control circuit including a relay magnet in series 35 with said gate contacts, a switch in the circuit with said line switch magnet which is closed by said relay magnet on actuation thereof, a second switch normally closed but which is opened by said relay magnet on ac- 40 tuation thereof, said elevator starting switch and said gate contacts being in circuit with said second switch, said circuit having less resistance than said control circuit, whereby if said elevator switch is closed before said 45 gate contacts, current will flow through said second switch and said relay magnet will not be actuated.

4. In an elevator safety appliance for 50 rope-controlled elevators, the combination with an elevator motor, an electric controller therefor, and a rope operating on said con-

troller, of a line circuit for said controller, a switch closed by movement of said rope in either direction, and means including 55 gate contacts for rendering said switch effective to cause current to be supplied to said electric controller only in case said gate contacts are first closed.

5. In an elevator safety appliance for 60 rope-controlled elevators, the combination with an elevator motor, an electric controller therefor, and a rope operating on said controller, of a line circuit for said controller, a switch closed by movement of said rope in either direction, and means including 65 gate contacts for preventing said switch from causing current to be supplied to said electric controller unless all of said gate contacts are first closed.

6. In an elevator safety appliance for 70 rope-controlled elevators, the combination with an elevator motor, an electric controller therefor, and a rope operating on said controller, of a line circuit for said controller, a line switch magnet for closing said circuit, a 75 switch closed by movement of said rope in either direction, said switch being in the circuit of said line switch magnet, a relay magnet, gate contacts for closing a circuit through said relay and magnet, and a switch 80 in said line switch magnet circuit closed by said relay magnet.

7. In an elevator safety appliance for 85 rope-controlled elevators, the combination with an elevator motor, an electric controller therefor, and a rope operating on said controller, of a line circuit for said controller, a line switch magnet for closing said circuit, a switch closed by movement of said 90 rope in either direction, said switch being in the circuit of said line switch magnet, a relay magnet, gate contacts for closing a circuit through said relay magnet, and means preventing closing of said elevator operating circuit if said rope-actuated switch is closed 95 prior to said gate contacts, said preventing means including a shunt circuit around said relay magnet, said shunt circuit including said rope-actuated switch.

Signed at New York city, New York, this 100
10th day of June 1920.

NEVILLE S. DICKINSON.
